UNITED STATES PATENT OFFICE.

WILLIAM G. ANDRUS, OF KALAMAZOO, MICHIGAN.

DAMPENING DEVICE FOR PAPER-CALENDERING MACHINES.

SPECIFICATION forming part of Letters Patent No. 746,655, dated December 15, 1903.

Application filed April 16, 1903. Serial No. 152,900. (No model.)

To all whom it may concern:

Be it known that I, WILLIAM G. ANDRUS, a citizen of the United States, residing at the city of Kalamazoo, in the county of Kalamazoo and State of Michigan, have invented certain new and useful Improvements in Dampening Devices for Paper-Calendering Machines, of which the following is a specification.

10 This invention relates to improvements in dampening devices for paper-calendering machines.

The objects of the invention are, first, to provide an improved paper-dampening device for calendering-machines by which the paper is properly dampened and there is no liability of spraying or spotting the same; second, to provide an improved paper-dampening device for calendering-machines by 20 which the amount of moisture delivered to the paper is under the perfect control of the operator; third, to provide an improved paper-dampening device for calendering-machines which is effective for the purpose and 25 at the same time simple in its construction and easy to operate.

Further objects and objects relating to structural details will definitely appear from the detail description to follow.

30 I accomplish the objects of my invention by the devices and means described in the following specification.

The invention is pointed out in the claims.

A structure embodying the features of my 35 invention is clearly illustrated in the accompanying drawings, forming a part of this specification, in which—

Figure 1 is an end elevation view of a structure embodying the features of my invention, 40 showing the relation of the parts, the calendering-rolls being illustrated in the conventional form, one side of the frame or support being removed. Fig. 2 is an enlarged detail transverse sectional view taken on a line corresponding to line 2 of Fig. 3. Fig. 3 is an 45 enlarged detail longitudinal sectional view taken on a line corresponding to line 3 of Figs. 1 and 2. Fig. 4 is a detail plan view, portions being broken away to show the relation of the parts.

In the drawings the sectional views are taken looking in the direction of the little

arrows at the ends of the section-lines, and similar letters of reference refer to similar parts throughout the several views. 55

Referring to the lettered parts of the drawings, the frame or support A for the calendering-rolls is of the usual or any desired construction, the rolls being arranged in the usual or any desired form. I support my improved dampening device in front of and adjacent to the first or top roll A' of the stack, so that it delivers steam to the under side of the paper m as it moves across the same as it is delivered to the roll A' from the guide- 65 roller m'.

I provide a steam-receptacle B, which is preferably of about the same length as the calendering-rolls. The receptacle B is provided with a removable top or cover C, which 70 is adapted to fit the same in a manner to effect a steam-tight joint. The top C is formed with upwardly-converging sides with an opening E at the top. This opening is controlled by sliding covers f, one at each side. The 75 cover C is strengthened by suitable cross-pieces g, to prevent springing or warping of the sides. The receptacle is provided with a screen-partition C'. This screen is supported by hoop-like ribs i to engage suitable supports on the walls of the casing, so that the same is firmly supported. The mesh of the screen C' is very fine, so that it prevents any spray from the steam-delivery pipe B' passing 80 therethrough. Steam is delivered into 85 the receptacle B by the pipe B', which is provided with a suitable cock c to control the same. The pipe B' is slightly inclined away from the supply-pipe b', so that the condensed steam will drip into the exhaust-pipe b, which 90 is also provided with a cock c. By the manipulation of these cocks c the amount of steam delivered through the perforations n of the pipe B' is under the perfect control of the operator. The receptacle B is provided 95 with an inclined bottom, so that the condensed steam is delivered through the drip-pipe D. The pipe B', which is passed entirely through the receptacle, also serves as a support for the same and is provided with 100 projecting trunnions e at each end, which are passed through suitable openings in the frame A of the machine. No additional support is required.

- In operation the steam is delivered into the pipe B' and through the perforations *n* into the lower chamber of the receptacle B. The screen C' prevents the same being forced directly against the paper *m* and prevents the formation of a spray, which causes the objectionable water spots upon the paper. It also causes the even distribution of the steam over the entire under surface of the paper as it is passed above the opening E. By the manipulation of the sliding doors *f* the opening may be adjusted to any width of paper. In reversing the paper, as is frequently done in calendering the same, the paper may in one operation be passed over one side of the machine and the opposite side closed, and the paper when reversed may be passed over the other side of the machine and the covers reversed. The result is that no excess of steam is delivered into the room, and it is delivered upon the entire surface of the paper in an even manner and in such quantities as may be desired, which is, of course, a very desirable feature.
- 25 My improved paper-dampening device for calendering-machines also has the advantage of being simple in its construction and easy to operate. It may be formed of sheet metal and is easily set up or disassembled.
- 30 I have illustrated and described the same in the form preferred by me on account of its simplicity in operation and economy in construction. I am aware, however, that it is capable of very considerable variation in structural details without departing from my invention.
- Having thus described my invention, what I claim as new, and desire to secure by Letters Patent, is—
- 40 1. In a paper-dampening device for calendering-machines, the combination of a receptacle B having a cover C with upwardly-converging sides; an opening E in the top thereof; sliding covers *f* for said opening; a removable screen-partition C' within said receptacle; a steam-supply pipe B' having perforations *n* in its upper side, arranged below said partition, said supply-pipe being adapted to support said receptacle; supply and exhaust pipes; and a drip-pipe for said receptacle, all coacting for the purpose specified.
- 45 2. In a paper-dampening device for calendering-machines, the combination of a receptacle B having a cover C with upwardly-converging sides; an opening E in the top thereof; sliding covers *f* for said opening; a removable screen-partition C' within said receptacle; a steam-supply pipe B' having perforations *n* in its upper side, arranged below said partition, said supply-pipe being adapted to support said receptacle; supply and exhaust pipes; and a drip-pipe for said receptacle, all coacting for the purpose specified.
- 50 3. In a paper-dampening device for calendering-machines, the combination of a receptacle B having a cover C with upwardly-converging sides; an opening E in the top thereof; sliding covers *f* for said opening; a removable screen-partition C' within said receptacle; a steam-supply pipe B' having perforations *n* in its upper side, arranged below said partition; supply and exhaust pipes for said pipe B'; stop-cocks for said supply and exhaust pipes; and a drip-pipe for said receptacle, all coacting for the purpose specified.
- 55 4. In a paper-dampening device for calendering-machines, the combination of a receptacle B having a cover C with upwardly-converging sides; an opening E in the top thereof; sliding covers *f* for said opening; a removable screen-partition C' within said receptacle; a steam-supply pipe B' having perforations *n* in its upper side, arranged below said partition; supply and exhaust pipes for said pipe B'; stop-cocks for said supply and exhaust pipes; and a drip-pipe for said receptacle, all coacting for the purpose specified.
- 60 5. In a paper-dampening device for calendering-machines, the combination of a receptacle B having a cover C with upwardly-converging sides; an opening E in the top thereof; sliding covers *f* for said opening; a removable screen-partition C' within said receptacle; a steam-supply pipe B' having perforations *n* in its upper side, arranged below said partition; supply and exhaust pipes for said pipe B'; stop-cocks for said supply and exhaust pipes; and a drip-pipe for said receptacle, all coacting for the purpose specified.
- 65 6. In a paper-dampening device for calendering-machines, the combination of a receptacle B having a cover C with upwardly-converging sides; an opening E in the top thereof; sliding covers *f* for said opening; a removable screen-partition C' within said receptacle; a steam-supply pipe B' having perforations *n* in its upper side, arranged below said partition; supply and exhaust pipes for said pipe B'; stop-cocks for said supply and exhaust pipes; and a drip-pipe for said receptacle, all coacting for the purpose specified.

7. In a paper-dampening device for calendering-machines, the combination of a receptacle B having a cover C with upwardly-converging sides; an opening E in the top thereof; sliding covers *f* for said opening; a removable screen-partition C' within said receptacle; a steam-supply pipe B' having perforations *n* in its upper side, arranged below said partition; supply and exhaust pipes for said pipe B'; stop-cocks for said supply and exhaust pipes; and a drip-pipe for said receptacle, all coacting for the purpose specified.

8. In a paper-dampening device for calendering-machines, the combination of a receptacle B having a cover C with upwardly-converging sides; an opening E in the top thereof; sliding covers *f* for said opening; a removable screen-partition C' within said receptacle; a steam-supply pipe B' having perforations *n* in its upper side, arranged below said partition, said supply-pipe being adapted to support said receptacle; supply and exhaust pipes for said pipe B'; stop-cocks for said supply and exhaust pipes, all coacting for the purpose specified.

9. In a paper-dampening device for calendering-machines, the combination of a receptacle B having a cover C with upwardly-converging sides; an opening E in the top thereof; sliding covers *f* for said opening; a removable screen-partition C' within said receptacle; a steam-supply pipe B' having perforations *n* in its upper side, arranged below said partition, said supply-pipe being adapted to support said receptacle; supply and exhaust pipes for said pipe B'; stop-cocks for said supply and exhaust pipes, all coacting for the purpose specified.

10. In a paper-dampening device for calendering-machines, the combination of a receptacle having upwardly-converging sides open at the top; an adjustable cover for said opening; a screen-partition within said receptacle; a steam-pipe having delivery-openings along the same arranged below said partition; supply and exhaust pipes for said delivery-pipe; means for controlling said supply and exhaust pipes; and a drip for said receptacle, for the purpose specified.

11. In a paper-dampening device for calendering-machines, the combination of a receptacle open at the top; an adjustable cover for said opening; a screen-partition within said receptacle; a steam-pipe having delivery-openings along the same arranged below said partition; supply and exhaust pipes for said delivery-pipe; means for controlling said supply and exhaust pipes; and a drip for said receptacle, for the purpose specified.

12. In a paper-dampening device for calendering-machines, the combination of a receptacle open at the top; an adjustable cover for said opening; a screen-partition within said receptacle; a steam-pipe having delivery-openings along the same arranged below said partition; supply and exhaust pipes for said delivery-pipe; means for controlling said supply and exhaust pipes, for the purpose specified.

13. In a paper-dampening device for calendering-machines, the combination of a receptacle open at the top; a screen-partition within said receptacle; a steam-pipe having de-

livery-openings along the same arranged below said partition; supply and exhaust pipes for said delivery-pipe; means for controlling said supply and exhaust pipes, for the purpose specified.

5 10. In a paper-dampening device for calendering-machines, the combination of a receptacle open at the top; an adjustable cover for said opening; a screen-partition within said receptacle; a steam-pipe having delivery-openings along the same arranged below said partition; supply and exhaust pipes for said delivery-pipe, for the purpose specified.

10 15. In a paper-dampening device for calendering-machines, the combination of a receptacle open at the top; a screen-partition within said receptacle; a steam-pipe having delivery-openings along the same arranged below said partition; supply and exhaust pipes for said delivery-pipe, for the purpose specified.

20 12. In a paper-dampening device for calen-

dering-machines, the combination of a receptacle having an opening at the top thereof; means for controlling the size of said opening; a screen-partition within said receptacle; means for delivering steam to said receptacle beneath said screen; and means for controlling the supply of steam delivered, for the purpose specified.

25 30. In a paper-dampening device for calendering-machines, the combination of a receptacle having an opening at the top thereof; means for controlling the size of said opening; a screen-partition within said receptacle; and means for delivering steam to said receptacle beneath said screen, for the purpose specified.

In witness whereof I have hereunto set my hand and seal in the presence of two witnesses.
